UNITED STATES PATENT OFFICE

1,991,788

FLUE

William G. Carter, Monrovia, Calif.

Application November 29, 1933, Serial No. 700,346

6 Claims. (Cl. 257—262)

My invention relates to flues for use in steam boilers, water heaters, condensers, refrigerators, and other devices, in which there is employed gaseous or other fluids of different temperatures inside and outside of the flues, and it is required to secure a rapid and efficient transmission of heat through the walls of the flue from the hotter of the two fluids to the cooler.

The purposes of my invention are to increase the efficiency of operation of such flues by forcing the fluid within the flue into contact with the surface of the flue so as to secure the most rapid and complete possible exchange of heat between two fluids. I have illustrated and described my device as applied to an ordinary household water heater, but it is evident that my improved flues may be employed in any form of device involving such an exchange of heat as is above described without departing from my invention.

I attain these purposes by the means shown in the accompanying drawing, in which Figure 1 is a vertical section drawn on the line 1—1 of Figure 3. Figure 2 is an elevation of a water heater embodying my device, a part of the outside wall 25 of the heater being broken away to show the flue inside, the view being taken at an angle of 90° to Figure 1, or on a normal to the line 1—1 of Figure 3. Figure 3 is a cross-section on the line 3—3 of Figure 1 and Figure 4 is a plan view of the upper extremity of the tube as will be more fully explained hereafter.

Referring more particularly to the drawing, 1 is the outer tank of a water heater of any approved construction. It may be of any size or form that 35 may be desired and may be used for the heating or cooling of other fluids than water if desired without departing from my invention. Indeed, the heater itself forms no part of my invention, which is confined to the flue.

2 is the main body of the flue itself, which is preferably formed initially as a plain cylindrical flue but is provided with a series of indentations 3, arranged in alternation on diametrically opposite sides of the flue. Near the upper extremity the flue 2 is welded, or tightly secured in any other suitable manner, into the top 4 of the heater and at the lower extremity into the bottom 5, so as to form water tight connections at both extremities.

50 A vertical flat partition 6 is mounted centrally in the flue and retained in position by a cross member 7. The member 7 has its extremities 12 removably connected to the flue 2 and is provided with a U shaped curve 8 so that if it is desired 55 to remove the partition 6, the curve 8 may be com-

pressed with pliers, or in any other suitable manner, and so released from the walls of the flue, permitting the partition to be withdrawn.

The partition 6 is constructed somewhat narrower than the internal diameter of the flue 2 so as to permit a complete circulation of the gases around it as shown by the arrows 9 in Figure 1, and as will be more fully explained hereafter.

The indentations 3 are of such a depth as to leave a small space 10 to permit the passage of gases between the indentation and partition. The lower extremity of the partition 6 is furnished with a suitable means 11 to maintain it in its central position and preferably terminates a short distance above the lower extremity of the flue as shown in Figure 1. This arrangement serves to somewhat steady and equalize the gases entering the flue from the combustion chamber and insure an equal supply of said gases to each side of the partition 6. This equality is further promoted by making the partition somewhat narrower than the internal diameter of the flue. While, however, the partition 6 is required to secure the highest degree of efficiency of operation, the flue itself as constructed with the use of the indentations 3 is highly efficient in operation without the partition, for as shown by the arrows the upward flowing gases are continually forced into close contact with the indentations in the flue and as they pass around the curve the alternating indentations again forces them not only into contact with itself but into contact with the opposite side of the flue. It will also be readily seen that this effect is greatly increased by the use of the partition which also operates as a retarding means to prevent the too rapid flow of the gases through the flue.

I claim as my invention and desire to cover by Letters Patent:

1. In a device of the character described, a flue provided with a plurality of inwardly extending indentations alternately positioned along its opposite sides, and having a longitudinally extending partition mounted within it. 40
2. In a device of the character described, a flue provided with a plurality of inwardly extending indentations alternately positioned along its opposite sides, and having a longitudinally extending partition removably mounted within it. 45
3. In a device of the character described, a flue provided with a plurality of inwardly extending indentations alternately positioned along its opposite sides, and having a longitudinally extending partition removably mounted approximately in the center of said flue. 50

4. In a device of the character described, a flue provided with a plurality of inwardly extending indentations alternately positioned along its opposite sides, and having a longitudinally extending partition removably mounted approximately in the center of said flue near to, but not in contact with, said indentations.
5. In a device of the character described, a flue provided with a plurality of inwardly extending indentations alternately positioned along its op-
- posite sides, and having a longitudinally extending partition removably mounted approximately in the center of said flue near to said indentations.
6. In a device of the character described, a flue provided with a plurality of inwardly extending indentations along its sides, and having a longitudinally extending partition mounted within it.

WILLIAM G. CARTTER.
